UNITED STATES PATENT OFFICE.

EUGENE J. LITTLE, OF BLUFFTON, INDIANA.

DUMPING-RECEPTACLE.

SPECIFICATION forming part of Letters Patent No. 607,603, dated July 19, 1898.

Application filed May 5, 1897. Serial No. 635,188. (No model.)

To all whom it may concern:

Be it known that I, EUGENE J. LITTLE, a citizen of the United States, residing at Bluffton, in the county of Wells and State of Indiana, have invented certain new and useful Improvements in Dumping - Receptacles, of which the following is a specification.

The object of my said invention is to produce a receptacle, to be located in floors and such like places, which may serve in the place of cuspidors and which shall normally be both closed and discharged of their contents, while easily capable of being brought into position for use.

15 An apparatus embodying my said invention will be first fully described and the novel features thereof then pointed out in the claims.

Referring to the accompanying drawings, which are made a part hereof and on which similar letters and figures of reference indicate similar parts, Figure 1 is a perspective view of a fragment of a car-floor in which a receptacle is placed embodying my present invention; Fig. 2, a sectional view alongside the end of the apparatus as seen from the dotted line 2 2 in Fig. 6, showing said apparatus in end elevation; Fig. 3, a transverse sectional view of the same as seen from the dotted line 3 3 in Fig. 6; Fig. 4, a transverse sectional view as seen from the dotted line 4 4 in Fig. 6; Fig. 5, a similar view to Fig. 4, but with the receptacle turned to its receiving position; and Fig. 6, a longitudinal sectional view as seen from the dotted line 6 6.

35 In said drawings the portions marked A represent the flooring and framework of a car-floor; B, the lower half, and C the upper half, of a casing secured thereto; D, a rotary dumping-receptacle; E, a lever for rotating said receptacle in one direction, and F a spring for returning or rotating the same in the opposite direction.

The casing-halves B and C are preferably 45 constructed so that their edges will fit together and interlock, as shown in the sectional views Figs. 4 and 5, but are not generally fastened together, although they may be. Each half is secured, preferably, to an appropriate part of the floor structure A. The upper half C has a thin flange the edges of which are neatly beveled or rounded off to fit

on top the floor, and screws 1, passing through this flange, serve to hold said casing-half in place. The lower casing-half B is similarly 55 secured by screws 2. These casings, as best shown in Figs. 4 and 5, fit substantially closely around the sides of the dumping-receptacle, so that practically no space is left for the passage of air. Bearings are formed in the ends 60 of the halves B and C for the gudgeons of the dumping-receptacle.

The dumping-receptacle D is provided with gudgeons d, which rest in the bearings provided therefor in the casing B and C. One 65 side is preferably flat, as shown, and when in its normal position at rest said flat side should be level with the top of the upper casing-half, so that the whole surface of the floor will be substantially level, as shown. Its intermediate sides are rounded to fit into the correspondingly concave portions of the casing B C. Its opposite side is open, as shown, and the receptacle as a whole is adapted to revolve, so that its lower or open side shall be 75 up when desired. On one of the gudgeons d is a pinion 3, by which it may be operated from the lever E.

The lever E is shown as pivoted or fulcrumed at 4 and has a segmental upper end 80 which is roughened or serrated, so that it may be conveniently operated by the foot, as will be presently described. It is further provided with a segmental rack which engages the pinion 3, as best shown in Fig. 3, 85 and is thus adapted to operate said pinion. Stops s are provided which limit the movement of the lever and cause the receptacle to stop at the desired position.

The spring F is connected at one end to the 90 casing part C or floor structure A and at the other end to the lever E and normally operates said lever to hold the receptacle with its flat or closed side upward.

When it is desired to turn the receptacle 95 to position for use, it is done by touching the foot to the serrated edge of the lever E, swinging said lever over on its pivot, and thus, through the segmental rack thereon and the pinion on the receptacle-gudgeon, revolving 100 said receptacle until its open side is up, as will be readily understood. When the receptacle has been used, the pressure of the foot is released and the receptacle will be

caused by the spring to return to the position shown in the drawings and obviously will dump the contents through onto the ground.

My invention is especially designed to be used in passenger-cars in lieu of cuspidors, and, particularly in smoking-cars, is calculated to promote cleanliness and sanitary conditions. It may be obviously used in other situations where similar work is required to be performed.

Having thus fully described my said invention, what I claim as new, and desire to secure by Letters Patent, is—

1. The combination, of a casing having concave sides, a revolute dumping-receptacle mounted in bearings in said casing and having two correspondingly convex sides, one of the remaining sides being open, mechanism for revolving the same, and a spring operating oppositely to said mechanism, whereby the closed side of said receptacle is normally held upward.

2. The combination of the casing parts B and C, the dumping-receptacle D mounted in bearings therein and provided with a pinion E on one of its journals, the pivoted rocking lever E formed with an operating-face on its

outer edge, the segmental rack-bar F mounted on one side of said lever and below said operating-face, with its cogs engaging the cogs of the pinion on the end of the receptacle-journal, and a spring connected to the operating mechanism to normally hold said receptacle to the limit of its movement in one direction, substantially as set forth.

3. The combination of a floor, a casing set in an orifice within said floor and substantially level therewith, a rotating dumping-receptacle mounted within said casing having one open and one closed side, the closed side being flat, thus maintaining the floor level when closed, and a lever having a segmental edge projecting through a slit in the casing to where it may be reached by the foot, and mechanism connecting said lever to said rotary dumping-receptacle below the floor, substantially as and for the purposes set forth.

In witness whereof I have hereunto set my hand and seal, at Bluffton, Indiana, this 1st day of May, A. D. 1897.

EUGENE J. LITTLE. [L. S.]
